UNITED STATES PATENT OFFICE.

JOHN D. BELANGER, OF CHICAGO, ILLINOIS.

OIL-PRESS.

981,970.

Specification of Letters Patent. Patented Jan. 17, 1911.

Application filed August 24, 1910. Serial No. 578,733.

To all whom it may concern:

Be it known that I, JOHN D. BELANGER, a citizen of the United States, residing at Chicago, in the county of Cook and State of Illinois, have invented a certain new and useful Improvement in Oil-Presses, of which the following is a specification.

My invention relates to improvements in oil presses and is illustrated in one form in the accompanying drawings, wherein—

Figure 1 is a side elevation; Fig. 2, a front view; Fig. 3, a section along the line 4—4 of Fig. 2; Fig. 4, a section along the line 5—5 of Fig. 3; Fig. 5, a detail view in perspective of one of the lining strips; and Fig. 6, a plan view on an enlarged scale of one of the oil collecting plates.

Like parts are indicated by the same letters throughout the several figures.

20 The adjacent supporting columns A carry at their tops the yokes A¹, A², which carry the bearings A³ in which rotates the eccentric shaft A⁴ carrying the drive pulley A⁵. The connecting rod A⁶ engages at one end 25 the eccentric shaft A⁴ and is pivotally mounted at the other upon the cross head A⁷ which is slidably mounted within the guides A⁸ which are held upon the columns A by means of the lugs A⁹.

30 The horizontal cross pieces B which are mounted upon the columns A carry the vertically disposed oil collecting plates B¹, B², which are provided upon their opposed sides with the diagonally disposed flanges B³ which are recessed to engage the solid end strips B⁴ and the vertically disposed parallel-sided lining strips B⁵ which form the pressure chamber B⁶. The columns A are held together against the cross pieces B, the 40 oil collecting plates B¹, B², and the end strips B⁴ by means of the bolts B⁷, B⁸, and nuts B⁹.

45 The oil collecting plate B² terminates in the downwardly extending flat rigid portion C to which is held the plate C¹ parallel with and overlapping the lining strips B⁵. In opposition to the plate C¹ is the flexible plate C² which is mounted upon the bottom of the oil collecting plate B¹ and serves as a continuation of the surface of the lining strips 50 which are carried upon the plate B¹. The lower extremity of the plate C is provided with the pedestal C³ in engagement with the cylinder C⁴ which rests against the wedge

C⁵ which is slidably adjustable along the 55 base of the column A by means of the screw C⁶ in the lug C⁷. The base of the plate C² is provided with the pedestal C⁸ in engagement with the cylinder C⁹ upon which are carried the links C¹⁰ having at the outer extremity the cylinder C¹¹ in engagement with one end of the lever C¹² which is fulcrumed about the boss C¹³ on the column A.

The yoke D upon the column A has the outwardly projecting screw D¹ which is in adjustable engagement by means of the nut D² with the rocking washer D³ which is in engagement with the outer end of the lever C¹².

The oil collecting plate B² is provided at its top with the upward extension E carrying the plate E¹ which overlaps the upper ends of the lining strips B⁵. The upper end of the oil collecting plate B¹ carries the horizontal plate E² which overlaps the 70 upper ends of the lining strips B⁵.

The endless bands of thick flexible filtering fabric F pass downward through the pressure chamber on either side bearing upon the lining strips B⁵ and pass upward about the outside of the pressure chamber 80 over the rollers F¹, F², F³, F⁴ and F⁵. The rollers F¹, F², F³, are adjustably mounted upon the lever F⁶ which is pivotally mounted upon the lug F⁷ upon the column A, and in engagement near its bottom with the lever 85 F⁸ in connection with the lever F⁹ upon which is adjustably mounted the weight F¹⁰. The rollers F⁴, F⁵, are rigidly and adjustably mounted to the frame work near the top of the pressure chamber and adapted 90 to guide the fabric as it enters said chamber.

The plunger G which is rectangular in cross section and in opposition to and adapted to enter the pressure chamber B⁶, is removably mounted upon the cross head A⁷ 95 by means of the reinforcing plate G¹ and screws G². The cross pieces H which engage the columns A in opposed pairs and which are located at right angles to the pressure chamber, carry the frames H¹ adjustably 100 mounted by means of the bolts H² in the slots H³, which frames are slotted at H⁴ to carry the slideable bearing blocks H⁵ in which are rotatably mounted the shafts H⁶ carrying the rollers H⁷ and intermeshing 105 gears H⁸. The bolts H⁹ screw-threaded in the frames H¹ and engaging the sliding bearings H⁵, operate to vary the distance be-

tween the rollers. The knives H^1 project from the surface of the rollers H^7 and are adapted to engage the material as it is fed between them and cut it into suitable lengths.

The chute K having the side walls K^1 is rigidly attached to the angle bar K^2 upon the columns A and discharges at a point immediately above the top of the pressure chamber. The chute K^3 is rigidly attached to the angle bar K^4 upon the columns A and is located beneath the oil collecting plates B^1 , B^2 , and communicates with the pipe K^5 , which is controlled by a valve and discharges into the storage tank not here illustrated.

The shaft H^6 carries the collar M having the lug M^1 adapted to engage during its rotation the star wheel M^2 to actuate the revolution counter or indicator M^3 .

The lining strips B^5 are parallel-sided and have one side scored with the microscopic file-like corrugations P and are provided at either end with the projecting lugs P^1 adapted to be engaged by suitable plates as described to hold them in position.

It will be evident that while I have shown in my drawing an operative device, still many changes might be made in the size, shape and arrangement of the parts without departing materially from the spirit of my invention.

The use and operation of my invention are as follows: The material such as seeds or fruits from which the oil or juices are to be extracted, is fed in a thin loose sheet to the top of the pressure chamber, the sheet being of substantially the same width as said chamber. The rectangular plunger which reciprocates in opposition to the pressure chamber is driven by the eccentric and forces an intermittently moving stream of material through the pressure chamber, the friction of the material against the walls of the chamber being sufficient to cause an enormous pressure to be exerted before motion takes place, and this pressure forces the liquids out of the solid material through the endless filtering belts of thick canvas-like fabric which cover the opposed side walls and which travel with the column or solid stream of material. The liquids are forced by the great pressure outward between the flat lining strips being aided in their travel by the fine corrugations on one side of each of the strips, being there caught by the vanes on the oil collecting plates and discharged downwardly into the oil discharge pipe. The filtering band which travels with the column of material arrests the discharge of the foots or fine particles and obviates the need of a separate filtering press since the fluid is discharged through said filtering bands in a clear condition. The enormous pressure operates in a sense to weld the fil-

tering bands and column of material together and in order to strip the column of material which takes the form of a continuous cake, the lower rollers over which the filtering bands pass are mounted upon levers which are forced outwardly by adjustable weights which weights are first raised by the adhesion of the bands to the cakes, and then exert their weight to overcome this adhesion, thus stripping the cakes. The rollers interposed below the pressure chamber may be adjusted in position corresponding to the thickness of the cake and the knives on such rollers operate to cut the cakes into suitable lengths. The pressure upon the cake by the rollers is so great that slipping does not take place and a revolution counter on the rollers indicates the number of cakes which has been discharged through the machine.

In order that, as the material passes through the pressure chamber and is compressed and loses its liquid, the friction may not decrease to too great an extent, the levers in connection with the flexible lower portion of the pressure chamber walls are tightened, thus decreasing the cross-sectional area of the pressure chamber or slot and the thickness of the cake is thereby reduced. By this means I provide a press which takes the crude material, removes all the liquid from it and delivers the liquid free from impurities or foots. My press, therefore, fulfils the function of both the usual oil press and the usual filtering press, and is at the time a continuously operative machine, since the reciprocatory motion of the plunger forces a continuous cake practically without intermission through the machine and the stream of oil and meal cake is to all intents and purposes uninterrupted and will continue as long as raw material is fed to the machine and power applied thereto.

I claim:—

1. An oil press comprising a pressure chamber open at one end to form an outlet, having closely joined parts which form oil-permeable inclosing pressure-receiving walls, a thin traveling filtering lining for the chamber, and a closely fitting pressure plunger reciprocating within said chamber.
2. An oil press comprising a pressure chamber open at one end to form an outlet, having oil-permeable inclosing pressure-receiving walls, a pressure plunger reciprocating therein, and a filtering lining for the chamber consisting of belts which travel with the material through the chamber along the pressure-receiving walls thereof.
3. An oil press comprising a pressure chamber open at one end to form an outlet, having oil-permeable inclosing pressure-receiving walls, a pressure plunger reciprocating therein, and a filtering lining for the

chamber, adapted to be carried by the material and therewith through the chamber along the pressure-receiving walls.

4. An oil press comprising a pressure chamber open at one end to form an outlet, having oil-permeable inclosing pressure-receiving walls, a pressure plunger reciprocating therein, and a filtering lining for the same consisting of a belt mounted on ten-

sion rollers and idlers exterior to the pressure chamber and adapted to travel through the chamber along the pressure-receiving walls with the material. 10
